UNITED STATES PATENT OFFICE.

AARON L. VOORHEES, OF CHICAGO, ILLINOIS, ASSIGNOR OF ONE-HALF TO HUGO FREELS,
OF CHICAGO, ILLINOIS.

INVERTED GAS-BURNER.

No. 903,033.

Specification of Letters Patent.

Patented Nov. 3, 1908.

Application filed June 9, 1906. Serial No. 829,864.

To all whom it may concern:

Be it known that I, AARON L. VOORHEES, a citizen of the United States, and a resident of Chicago, in the county of Cook and State 5 of Illinois, have invented certain new and useful Improvements in Inverted Gas-Burners, of which the following, when taken in connection with the drawing accompanying and forming a part hereof, is a full and complete 10 description, sufficient to enable those skilled in the art to understand, make, and use the same.

This invention relates to inverted gas burners provided with a Bunsen burner and 15 a mantle; and the object of the invention is to obtain a burner by means of which, when the same has burned until the supply pipe, adjacent to the mantle, is heated, sufficient gas will be supplied and with sufficient force to 20 induce a sufficient supply of air so that no smoke will be produced or emitted by the burner and a blue flame, as it is called, will continuously be produced.

A further object of the invention is to obtain 25 a burner of the kind named which may be easily attached to an ordinary gas pipe, in place of the ordinary tip or in place of an ordinary Wellsbach burner, by one not particularly skilled in the art, and properly adjusted to burn as desired and to produce a blue flame.

In the drawing referred to as forming a part of this specification Figure 1 is a side elevation of an inverted burner embodying 35 this invention, showing a mantle thereon in suitable position for use. Fig. 2 is a side elevation, on an enlarged scale, of the end of the pipe to which an inverted burner embodying this invention may be attached. Fig. 3 is a vertical sectional view of the Bunsen burner forming a part of this invention. Fig. 4 is a vertical sectional view, on an enlarged scale, of the upper end of the Bunsen burner forming a part of this invention, and 45 of the parts adjacent thereto, with the lower end of the goose neck of the burner. Fig. 5 is a vertical sectional view of a diminishing thimble forming an element in the device embodying this invention. Fig. 6 is a vertical 50 sectional view of a modification of the diminishing ring or thimble of the device. Fig. 7 is an elevation of the base of the needle valve forming an element in the gas burner

embodying this invention, and Fig. 8 is a top plan view of the base of the needle valve. 55

A reference letter applied to designate a given part is used to indicate such part throughout the several figures of the drawing, wherever the same appears.

A is an ordinary ell.

B is a Bunsen tube. Tube B is provided with the base C and with air regulating sleeve E.

F is a perforated tube.

G is an adjustable diminishing tube (see 65 Figs. 2 and 3).

The air apertures in tube F are lettered f, f. Base C consists of the knurled part C' provided with screw threads therein fitting over the ordinary screw threads of 70 gas ell A, the screw threaded parts C² and C³ and the needle C⁴. At the base of needle C⁴ there are provided the holes C⁵ through which gas may flow to around the needle C⁴ and underneath the cap D. Cap D is provided with internal screw threads fitting 75 over the screw threads C³ of base C, and with an aperture fitting over C⁴ of base C so that by turning such cap the aperture is more or less closed by needle C⁴. The foregoing described needle valve and base obtained by base C and cap D is the ordinary construction.

K is the goose neck of the inverted burner and L is the mantle thereof. In the device 85 embodying this invention the goose neck K is attached to the Bunsen burner B by means of the interposed support M.

Support M preferably comprises the enlarged part m of the end of the goose neck 90 K, and the tube m' provided with the enlarged part m² engaging with enlarged part m of goose neck K, and provided with the enlarged part m³ forming a wind guard to air apertures f, f, in tube F.

m⁴ is a groove in the upper end of tube m' to prevent such tube from falling down on tube E.

It will be observed that diminishing tube G is of less area at the upper and discharge 100 end thereof (lettered g) than is the area of the passage through the goose neck K (shown in the part of such goose neck adjacent to the enlarged part m, in Fig. 4).

g' is a ring or ferrule on the upper end of 105 diminishing tube G preferably used when

such tube is pressed or formed up from an ordinary tube. When such tube is made by reaming out a tube having thick walls as at 5 g^2 in tube G' in Fig. 5 of the drawing, the ring or ferrule g' is not used.

By the enlarging of the upper end of the tube m' as at m^2 , and the enlarging of the lower end of goose neck K is at m , mixing chamber n (Fig. 4) is obtained in which the 10 gas and air discharged from diminishing tube G are thoroughly mixed before the same are delivered therefrom in the goose neck K.

The diminishing tube G may be raised or 15 lowered in tube F to more or less cover apertures f, f , for the adjustment of the air supply to the Bunsen burner.

I find in discharging the gas and air from 20 the Bunsen burner to the goose neck K through an aperture of less area than the

area of the goose neck that when the end of 25 the goose neck adjacent to the mantle L becomes heated the discharge of such combined air and gas into such goose neck is substantially the same as before the heating.

Having thus described my invention what 30 I claim as new and desire to secure by Letters Patent is:—

In a gas burner, the combination of a gas nozzle, a tube secured to said nozzle and having air admission openings adjacent thereto, a longitudinally movable mixing cup frictionally held within the tube and arranged to vary the size of the air admission opening, said cup having an exit of less area than its entrance.

AARON L. VOORHEES.

In the presence of—

CORA A. ADAMS,

CHARLES TURNER BROWN.
